UNITED STATES PATENT OFFICE.

HERMAN M. LOEBER, OF BEATRICE, NEBRASKA, ASSIGNOR TO DEMPSTER MILL MANUFACTURING CO., OF BEATRICE, NEBRASKA, A CORPORATION OF NEBRASKA.

WINDMILL CONSTRUCTION.

Application filed November 15, 1923. Serial No. 674,849.

My invention relates to windmill construction.

One of the objects of my invention is to improve the construction of self-oiling windmills.

A further object of my invention is to provide an improved back-gearred self-oiling windmill.

A further object of my invention is to provide improved means for oiling the cross head of the windmill.

A further object of my invention is to provide an improved brake for the wind wheel.

15 Further objects will appear from the description and claims.

In the drawings in which an embodiment of my invention is shown—

Figure 1 is a plan view partly in section of 20 the windmill construction;

Fig. 2 is a side elevation partly in section;

Fig. 3 is a vertical sectional view;

Fig. 4 is an enlarged sectional view of an oil scraper carried by the cross head;

25 Fig. 5 is a fragmentary view showing the oil scraper;

Fig. 6 is a section on the line 6—6 of Fig. 2;

Fig. 7 is a section on the line 7—7 of 30 Fig. 2; and

Fig. 8 is a section on the line 8—8 of Fig. 2.

Referring now to the drawings in detail, the construction shown therein comprises a 35 main frame or head 10, on which the wind wheel 11, the vane 12 and the transmission from the wind wheel to the pump rod 13 are mounted, a rotatable tubular stem 14 on which the head 10 is mounted, and pull-out 40 mechanism 15 for throwing the mill out of gear.

The head 10 is designed to provide a substantial oil reservoir, from which oil is supplied to all of the working parts.

45 The transmission from the wind wheel 11 to the pump rod 13 comprises a main shaft 16 on which the wind wheel is mounted, a pair of pinions 17 and 18 secured on the shaft 16, a pair of gears 19 and 20 meshing 50 with the pinions 17 and 18 respectively; a pair of pitmen 21 and 22 pivoted at their lower ends to the gears 19 and 20 respectively and operating between said gears, and a cross head 23 to which the upper ends of

the pitmen are pivotally connected at 24, 55 the pump rod 13 being connected with the cross head at 25.

The main shaft 16 is provided with main bearing sleeves at 26 and 27, and is provided 60 an end bearing at 28.

The gears 19 and 20 are mounted on short journal members or bearing hubs 29 and 30 having projecting portions 30^a to keep the gears in place, secured to the head 10 by means of bolts 31. This mounting of the 65 gears enables the pitmen 21 and 22 and the cross head 23 to operate in the space between the gears.

The cross head 23 is mounted on vertical 70 cross head guides 32 and 33, and one side of the cross head is extended downwardly so that its lower end dips in the oil 34 in the oil reservoir on the lower portion of the stroke as shown in Fig. 3.

The bearing sleeves 26 and 27 are mounted 75 in a tubular portion 35 of the head 10. For supplying oil to these bearing sleeves a notched ring 36 (Figs. 2 and 6) is provided, which rotates with the main shaft 16. In order to maintain this oiling ring snugly 80 over against the end of the bearing sleeve 27, a tapering collar 37 is provided, mounted on the main shaft 16, the oiling ring being provided with a corresponding inner tapering surface at 38. These tapering surfaces 85 will cause the oiling ring to be maintained in snug engagement with the end of the bearing sleeve 27, and will cause oil carried up by the oiling ring to be supplied to this bearing sleeve. The oil will be carried 90 along the main shaft 16 by the rotation of the shaft to supply oil to the outer bearing sleeve 26.

In order to insure the return of the oil 95 from the outer end of the shaft to the reservoir, a floatable oil scraper 39 is provided (Figs. 2 and 7) having an inclined scraper portion 40, which shears the oil from the shaft, and causes it to drip down into the passage 41, which returns it to the main oil reservoir. A coil compression spring 42 is provided for holding the oil scraper 39 snugly up against the lower side of the shaft.

The oil level in the reservoir is ordinarily such that the lower ends of the pitmen will dip therein, but if not, the gears 19 and 20, the lower sides of which dip into the oil,

will carry up enough oil to supply the pitmen connections.

In order to supply oil to the pivotal connection between the pitmen and the cross head, an oil scraper 43 is provided (Figs. 3, 4 and 5). This oil scraper is mounted to slide on the cross head guide 32, and is guided independently of the cross head, so that any wear on the bearing 44 of the cross head will not affect the operation of the oil scraper, and so that none of the horizontal component of the pitman thrust has to be carried by this oil scraper. In order to drag the oil scraper down with the cross head the scraper is provided with a pair of lugs 45 and 46 located underneath the ears 47 and 48 on the cross head.

In order to conduct the oil which is scraped from the cross head guide 32, to the pivotal connection 24 of the pitmen, the scraper is provided with an inclined oil passage 49, which conducts the oil to the oil hole 50. In order to provide some lubrication for the auxiliary cross head guide 33, an oil hole 51 leads from the pivotal connection 24.

The pull-out construction for throwing the mill out of the gear comprises a pull chain 52, running over the pulleys 53 and 54, and a rock arm 55, to which the chain 52 is connected at 56. This rock arm 55 is mounted on the vertical pivoted pin 57 on which the vane 12 also is pivotally mounted, and is provided with an abutment portion 58 which engages the strut 59, which extends between and is secured to the vane members 60 and 61. This loose engagement between the rock arm 55 and the strut 59 enables the windmill to regulate itself in the wind by permitting pivotal movement of the head with respect to the vane without interference from the pull-out rock arm.

In order to provide a cushioning effect for the throwing in and out of gear of the mill, a pivoted buffer member 62 is provided, having an abutment portion 63 for limiting the throwing in movement of the mill, and another abutment portion 64, for limiting the throwing out movement of the mill. This buffer or cushioning member 62 is pivotally mounted on the same pin 57 on which the vane stem and throw-out arm are pivoted. In order to provide a connection between the buffer member 62 and the vane 12, which will yield in both directions, a pair of coil compression springs 65 and 66 are provided, through which the connecting rod 67 extends. One end of this connecting rod is pivotally secured to the vane stem, and the other end extends through an opening in the lug 68 formed on the buffer member. The buffer springs are held in place on the connecting rod by means of nuts 69 and 70 threaded on the connecting rod. In order to throw the mill into gear when the pull-

out chain is released, a heavy coil tension spring 71 is provided, one end of which is secured to the vane stem, and the other end of which is secured to a hook 72 mounted on the head 10.

In operation, when the pull-out chain 52 is released to allow the spring 71 to throw the mill into gear, the abutment portion 63 of the buffer member engages the side of the head 10, and the buffer spring 66 acts as a cushion to bring the further relative movement between the head and the vane stem to a stop.

When the mill is thrown out of gear by pulling down on the chain 52, the abutment portion 64 of the buffer member engages the side of the head 10, whereupon the relative motion between the head and vane stem is brought to a stop by the cushioning spring 65.

In order to hold the wind wheel against rotation when the mill is out of gear, the hub 73 of the wind wheel is provided with an internal annular braking surface at 74 with which cooperates an internal expanding brake band 75. A coil tension spring 76 (Fig. 8) tends to hold this brake band out of contact with the braking surface. The brake band is mounted on a bracket 77, secured to the tubular portion 35 of the head.

The brake band 75 is forced outwardly into braking position when the mill is thrown out of gear by means of a bell-crank 78 pivotally mounted to swing about a vertical axis by means of a pin 79 secured to the under side of the tubular portion 35. This bell-crank is operated from the pull-out arm 55 by means of a link 80 pivotally connected at 81 to the bell-crank, and pivotally connected at 82 to an arm 83 formed integral with the pull-out arm 55.

While I have shown but one form of my invention, it is obvious that it may be embodied in other forms covered and defined by the appended claims.

Having thus described my invention, what I claim as new and desire to secure by Letters Patent of the United States is:

1. In a windmill, the combination of a wind wheel, a driving shaft, a main frame having a vertical pivoted tubular axle, a lubricant containing chamber in said frame, bearing hubs rigidly connected to the inner sides of oil chamber, gear wheels mounted upon said hubs, the hubs having projecting shoulders to keep said gear wheel in place, pinions mounted upon the driving shaft for operating the gears, guide rods, a cross head working upon said guide rods, one side of which extends downwardly and dips into the lubricant upon its downward stroke, and pitmen connecting the cross head and gears for operating the pump rod.

2. In a windmill, the combination of a main frame arranged to contain lubricant,

- a wind wheel, a wind wheel shaft, a pump rod, power transmitting mechanism connecting the wheel shaft with the pump rod including a cross head, guide rods for said 5 cross head, the cross head being arranged to dip in the oil chamber on the downward stroke and carry oil up on the guide rods, and an oil scraper slidably mounted on said guide rods and loosely connected to the cross 10 head, said oil scraper having a surface adapted to shear the oil from the guide rods and a groove to lead the oil to other parts to be lubricated.
3. A windmill comprising a wind wheel, 15 a pump rod, an oil reservoir, and transmission from said wheel to said rod, comprising a pair of spaced gears and vertically reciprocable cross head driven by said gears, said oil reservoir serving to maintain a 20 supply of oil between said gears, and said cross head being reciprocable in the space between said gears and extending downwardly to dip into said oil supply.
4. A windmill construction comprising a 25 wind wheel, a pump rod, an oil reservoir, vertical cross head guides, and transmission from said wheel to said pump rod, comprising a pair of spaced gears and a cross head mounted on said guides and driven by said 30 gears, said oil reservoir serving to maintain a supply of oil between said gears, said cross head guides being located between said gears, and said cross head being reciprocable in the space between said gears and extending 35 downwardly to dip into said oil supply.
5. A windmill construction comprising a wind wheel, a pump rod, an oil reservoir, and transmission from said wheel to said pump rod, comprising a pair of spaced 40 gears, the lower portions of which operate in the oil in said reservoir and a cross head driven by said gears, said cross head being reciprocable in the space between said gears and extending downwardly to dip into said 45 oil reservoir.
6. A windmill construction comprising a wind wheel, a pump rod, an oil reservoir, and transmission from said wheel to said rod comprising a pair of spaced gears, a pair of 50 pitmen operating between said gears and pivotally connected at one end with said gears respectively, a cross head to which the other ends of said pitmen are pivotally connected, said oil reservoir serving to maintain 55 a supply of oil between said gears, and said cross head being reciprocable in the space between said gears and extending downwardly to dip into said oil supply.
7. A windmill construction comprising a 60 wind wheel, a pump rod, an oil reservoir, and transmission from said wheel to said rod, comprising a pair of spaced gears, a pair of pitmen pivotally connected at one end with said gears respectively, and a cross 65 head to which the other ends of said pitmen
- are connected, said oil reservoir serving to maintain a supply of oil between said gears, and said cross head being reciprocable in the space between said gears and extending downwardly to dip into said oil supply. 70
8. A windmill construction comprising a wind wheel, a shaft on which said wind wheel is mounted, a pair of spaced pinions mounted on said shaft, a pump rod, a transmission from said pinions to said pump rod, comprising a pair of spaced gears meshing with said pinions respectively, and a cross head driven by said gears, and an oil reservoir serving to maintain a supply of oil between said gears and said cross head being reciprocable in the space between said gears, 75 to dip into said oil supply. 80
9. A windmill construction comprising an oil reservoir, a vertical cross head guide, a cross head, and an oil scraper actuated by 85 said cross head and guided by said cross head guide independently of said cross head.
10. A windmill construction comprising an oil reservoir, a vertical cross head guide, a cross head, and an oil scraper actuated by 90 said cross head and guided by said cross head guide independently of said cross head, said oil scraper being provided with an oil passage for conducting the oil scraped from the cross head guide to a part to be lubricated. 95
11. A windmill construction comprising an oil reservoir, a vertical cross head guide, a cross head, a member pivotally connected with said cross head and an oil scraper actuated by 100 said cross head and guided by said cross head guide independently of said cross head, said scraper being provided with a passage for conducting the oil scraped from said cross head guide to said pivotal connection. 105
12. A windmill construction, comprising a wind wheel, a shaft on which said wheel is mounted, a bearing for said shaft, an oil reservoir, means for supplying oil to said shaft from said reservoir, means for preventing oil from escaping beyond the end of said bearing, comprising a spring pressed scraper floatably engaging said shaft, and means for returning the oil from said scraper to said reservoir, said scraper engaging the under side of said shaft. 110
13. A windmill construction comprising a wind wheel, a horizontal shaft on which said wheel is mounted, a bearing for said shaft, an oil reservoir and means for supplying oil to said bearing from said reservoir, comprising a collar on said shaft tapering towards said bearing and a ring carried by said collar and engaging the tapering periphery thereof, whereby said ring is maintained in position against said bearing. 120
14. A windmill construction comprising a wind wheel, a horizontal shaft on which said wheel is mounted, a bearing for said shaft, 125

- an oil reservoir and means for supplying oil to said bearing from said reservoir, comprising a collar on said shaft tapering towards said bearing and a ring carried by 5 said collar and engaging the tapering periphery thereof, whereby said ring is maintained in position against said bearing, said ring having an internal tapering surface engaging the tapering periphery of the collar.
- 10 15. A windmill construction comprising a wind wheel, a horizontal shaft on which said wheel is mounted, a bearing for said shaft, an oil reservoir and means for supplying oil to said bearing from said reservoir, 15 comprising a collar on said shaft tapering towards said bearing and a ring carried by said collar and engaging the tapering periphery thereof, whereby said ring is maintained in position against said bearing, and 20 means whereby said ring is caused to rotate with said collar.
16. In a windmill, the combination of a main frame having a reservoir to contain lubricant, a pump rod, a cross-head operating 25 said pump rod, guides for said cross-head, bearing hubs rigidly secured to the inner sides of said frame, gears journaled independently thereon, and pitman connections between the gears and crosshead.
- 30 17. In a windmill the combination of a wind-wheel, a driving shaft, a supporting frame having an oil chamber therein, bearing hubs rigidly fastened to the inner sides of said oil chamber, gears journaled independently upon said hubs, pinions rigidly mounted on the driving shaft for operating 35 said gears, a crosshead for operating the pump rod and pitman connections between the gears and crosshead.
- 40 18. In a windmill the combination of a wind-wheel, a driving shaft, a supporting frame having an oil chamber therein, pinions rigidly mounted on said driving shaft, bearing hubs fastened to the inner sides of 45 said oil chamber and gears independently journaled thereon and driven by said pinions.
19. A windmill construction comprising a wind wheel, a shaft on which said wheel is mounted, a tubular member non-rotatable 50 with said shaft through which said shaft extends, said wind wheel being provided with an internal brake drum, and an ex-
- panding brake band mounted on said tubular member for engagement with said internal brake drum. 55
20. A windmill construction comprising a wind wheel, a head on which said wind wheel is mounted, said head being swivelled about a vertical axis, a vane pivotally mounted on said head to swing about a vertical axis with respect to said head, and buffer means acting between said head and vane comprising a buffer member movable with the vane to swing about a vertical axis 60 and cooperating with the head at both extremes of the swinging movement to limit the swinging movement, said buffer member having a yielding connection with said vane. 65
21. A windmill construction comprising a wind wheel, a head on which said wind wheel is mounted, said head being swivelled about a vertical axis, a vane pivotally mounted on said head to swing about a vertical axis with respect to said head, and 70 buffer means acting between said head and vane comprising a buffer member movable with the vane to swing about a vertical axis and cooperating with the head at both extremes of the swinging movement to limit 75 the swinging movement, said buffer member having a yielding connection with said vane, said yielding connection comprising a pair of oppositely acting springs. 80
22. A windmill construction comprising a wind wheel, a head on which said wind wheel is mounted, said head being swivelled about a vertical axis, a vane pivotally mounted on said head to swing about a vertical axis with respect to said head, and 90 buffer means acting between said head and vane comprising a buffer member movable with the vane to swing about a vertical axis and cooperating with the head at both extremes of the swinging movement to limit 95 the swinging movement, said buffer member having a yielding connection with said vane, said yielding connection comprising abutment means on said buffer member, oppositely acting coil springs cooperating with 100 said abutment means and a rod secured to said vane and extending through said coil springs.

In witness whereof, I have hereunto subscribed my name.

H. M. LOEBER.
